(57) CLAIM

The ornamental design for a battery, as shown and described.

DESCRIPTION

FIG. 1 is a top, front, right side perspective view of a battery. FIG. 2 is a bottom, front, right side perspective view of the battery of FIG. 1.

FIG. 3 is a top plan view of the battery of FIG. 1.

FIG. 4 is a bottom plan view of the battery of FIG. 1.

FIG. 5 is a rear elevation view of the battery of FIG. 1.

FIG. 6 is a front elevation view of the battery of FIG. 1.

FIG. 7 is a left side elevation view of the battery of FIG. 1; and,

FIG. 8 is a right side elevation view of the battery of FIG. 1.
